JEWEL ORNAMENTED WITH STONES

Salomon (dit Charles) Arpels, Paris, France, assignor to Société Van Cleef & Arpels, Paris, France, a corporation of France

Application May 1, 1936, Serial No. 77,423
In France February 13, 1936

3 Claims. (Cl. 63—28)

Systems for fitting and mounting precious stones are known in which the stones are provided with suitable grooves adapted to engage with slideways on a mounting base in such manner that their girdles adjoin one another. This system permits of obtaining an invisible mounting.

Such a system is, for instance described in French Patent No. 764,966, of December 2, 1933.

However, systems of this kind are suitable only for the mounting of stones the dimensions of which are identical or vary constantly in one direction from one end of the slideway toward the other end. On the other hand, even with stones having similar dimensions, this arrangement does not permit of obtaining patterns of complicated shape substantially different from a rectangle, a trapezium, a cylinder, or a cone. In particular, it does not permit of easily arranging the stones in complicated curve lines or on twisted surfaces.

The object of the present invention is to provide a system of mounting which permits of producing a pattern of any desired shape or arrangement in which the dimensions of the stones do not always vary in the same direction and which may constitute a surface as complicated as it is desired.

The essential feature of the present invention consists in providing, in the ornamental jewel design, a removable part, which will be hereinafter called a locking key or wedge, devised in such manner that when it is removed from its assembled position the stones can easily be fitted in the remainder of the jewel, either by causing them to slide in grooves, or by taking advantage of the elasticity of the metallic parts of the mounting, after which the key is replaced into position and positively prevents the stones already fitted from leaving the mounting.

In a preferred embodiment of the invention, the visible surface of the key is itself provided with stones arranged in such manner that, once the key is in position, the stones it carries contribute to the ornamental aspect of the whole and, therefore, said key is not visible.

It should be well understood that the application of the principle above set forth, according to the invention, depends upon the specific conditions to be complied with in every case.

Preferred embodiments of the present invention will be hereinafter described, with reference to the accompanying drawing, given merely by way of example, and in which:

55 Figs. 1 and 2 are a front view and a side view,

respectively, of a first embodiment of the invention, with the key in position;

Fig. 3 is a cross section of the ring shown by Fig. 4 taken on section line III—III;

Fig. 4 is a view similar to Fig. 1, showing the mounting with the locking key removed, and without the stones inserted in their slideways;

Fig. 5 is a separate sectional view diagrammatically showing the key;

Fig. 6 is a view similar to Fig. 4, but with the stones in position;

Fig. 7 is a plan view of another embodiment of the invention;

Fig. 8 is a similar view of a modification;

Fig. 9 is a perspective view of the key of the jewel shown by Fig. 8;

Fig. 10 is a cross sectional view of the locking key shown by Fig. 9;

Fig. 11 is a view similar to Fig. 9, but with the stones in position in the key; the jewel being also visible on this figure.

The first example relates to a ring including a plain portion 1, for instance of metal, carrying an ornamental pattern of stones 2, disposed in such manner that the whole forms a block of 25 solid appearance.

As is apparent in the drawing, the ornamental portion of the jewel has no inlet face through which the stones could be inserted successively in position by sliding them in slideways.

On the contrary, according to the invention, the stones can be inserted into position in the following manner: The jewel is made as shown by Fig. 4, that is to say the portion intended to carry the stones includes a plurality of slideways formed by flat bands 4 extending substantially parallel to and spaced from the surface of the base, and the base is cut away at 5, so as to form a gap having oblique sides. Into this gap can be fitted in a very precise manner a kind of 40 wedge 6, which constitutes the key.

On the other hand, in the example, the size of the stones located in plane A B (Fig. 1) is greater than that of the stones located on either side of this plane. Accordingly, the intervals between bands 4 are chosen in such manner that they are larger close to the edges of gap 5 than in portions 7 where said bands are joined to portion 1.

The section of bands 4 is clearly visible in Fig. 50 3 of the drawing.

In order to fit the stones in position, wedge or key 6 is removed. The stones are successively inserted in the slideways between the bands 4 on either side of gap 5, the smaller stone being in- 55

serted first. When this operation is completed, wedge 6 is restored into position and it is fixed, for instance by invisible soldering. The ornamental part of the ring is thus fitted with stones which cannot be accidentally detached.

Of course, locking wedge or key 6 may be of any structure whatever and it may constitute a particular pattern in itself. However, the system may be devised in such manner that this wedge 10 does not interfere with the regular aspect of the stone setting. For this purpose, it suffices to make use of a wedge-shaped key, as shown by Fig. 5, consisting of a metal sheet 8, curved in V-shaped fashion and the edges of which are provided with flanges as indicated by numeral 9. Suitable cut stones are inserted between these flanges, either by sliding them longitudinally or by springing the flanges 9 apart owing to the elasticity of sides 8. Key 6 shall then have the external aspect shown by Fig. 6. The stones are so arranged and dimensioned that, once the key is restored into position, the whole forms a regular setting in which the stones carried by the key do not distinguish from those carried by the fixed 25 part of the ring. It will be impossible for a person, not an initiate, to know how the stones have been assembled and fixed.

The second example consists of an ornamental design representing one or several leaves. In this case, the lines that separate from one another the stones of the jewel are of complicated curvature. Furthermore (as this cannot be clearly seen on the drawing) the surfaces have curvatures which vary widely from one point to another, as well from the point of view of the radius of curvature as from that of the direction of the curvature. Complicated surfaces of this kind could not be fitted with stones merely by means of slideways along which the stones are slipped, by starting from the lateral edge of the jewel.

According to the present invention, one or several groups of juxtaposed stones are chosen in such manner that once this group or these groups has, or have, been removed another area of the jewel can easily be fitted, by successively placing the stones in suitable directions on slideways provided for this purpose. These removable groups of stones shall be chosen in such manner as to form a single element forming a key. Therefore, it will suffice to remove the key for being able to easily fit the remainder of the jewel with stones. Then the key is restored into position, locking the other stones.

The shape of the key shall of course vary according to whether it is desired to fit the jewel with stones by causing them to slide along slideways or by making use, eventually, of the elasticity of the various bands of metal between them when the stones are set.

Fig. 7 shows, in plan view, a jewel consisting of a base or support, in the form of a tree leaf, covered with a plurality of stones arranged in adjoining relationship to one another, so as to form a kind of pavement. The lower part of Fig. 7 shows the support or base with the stones set in position, whereas the upper part of the same figure, in which the stones are absent, shows the small metal bands, such as 13, between which said stones are to be inserted. The key 11 is disposed, in this case, in such manner as to permit of fitting most of the stones through the elasticity of the various transverse bands 13.

The key consists of a marginal portion 11. All the metal bands, with the exception of bands 12

and 14, are sufficiently elastic for permitting of setting the stones in position merely through their elasticity.

Bands 12 and 14, which are adjacent to key 11, are not flexible. The stones are inserted in position between the various bands 13 by making use of the elasticity of these bands, once key 11 has been removed, and the stones corresponding to bands 12 and 14 are brought into position by sliding them laterally on either side of the opening produced by the removal of key 11 until these rows engage the end locking surfaces 10. This being done, key 11, itself fitted with its stones, is inserted in position and thus locks all the stones in the respective positions they now occupy. This is due to the fact that the stones of bands 12 and 14 can no longer slide therealong and all the other rows, to wit, those between bands 13, are also locked.

In Figs. 8 to 11, I have shown another embodiment which also relates to the case of a leaf-shaped jewel carrying a pavement of precious stones. In this embodiment, there is provided, on either side of the central rib of the leaf, a pair of parts 15, parallel to said rib, and which can be removed so as to leave empty spaces 16, 16'. The various bands 17 between which the stones are caused to slide for inserting them in position are, in this case, substantially at right angles to the central rib of the leaf. Therefore, after having removed keys 15, the stones are successively inserted by causing them to slide between bands 17. Once this operation has been completed, keys 15, previously fitted with their stones, are inserted in the corresponding empty spaces 16, 16', and they lock all the stones in position. The keys are fixed in position through any suitable means, for instance by soldering.

Fig. 9 is a perspective view of the key, without its stones.

Fig. 10 shows the same key, in transverse sectional view.

Fig. 11 shows the key, fitted with its stones, ready to be inserted in position, this figure also showing the leaf ready to receive the keys.

Like the key 6 shown by Fig. 5, key 15 consists of a gutter-shaped thin metal envelope, provided with two inwardly extending flanges 9 which serve to keep the stones in position. These stones may be fitted in position either by slipping them from the end of gutter-shaped element 15, or by making use of the elasticity of the walls of said element.

In a general manner, while I have, in the above description, disclosed what I deem to be practical and efficient embodiments of the present invention, it should be well understood that I do not wish to be limited thereto as there might be changes made in the arrangement, disposition and form of the parts without departing from the principle of the present invention as comprehended within the scope of the appended claims.

What I claim is:

1. A jewel or the like which comprises, in combination, a support, substantially parallel elastic bands carried by said support, precious stones adapted to fit between said bands and to be removably held therebetween owing to the elasticity of said bands and a locking piece adapted to fit in said support so as to lock the whole of the bands and the stones present between said bands, whereby said bands can no longer be deformed so as to permit of the stones escaping from between them.

2. A jewel or the like which comprises, in combination, a support, a plurality of substantially parallel rigid bands, stones adapted to fit between said bands, said support being provided with an opening so that the stones can be slipped between said bands from the edges of said opening, and a locking piece fitting exactly in said opening, so as to lock all the stones between said bands.
- 5 3. A jewel or the like comprising in combination a support, bands extending substantially parallel to each other placed on said support and spaced apart laterally, providing slideways to engage precious stones; a stop surface at the one end of each of said slideways; rows of precious stones in said slideways engaged by said bands and abutting said stop surfaces, said rows being held against movement by said bands and said stop surfaces in all but one direction which is parallel to the surface of the support; and a locking member fixed on said support so as to lock the stones in the direction in which they are not held by said bands and stop surfaces.
- 10
